UNITED STATES PATENT OFFICE

ARTHUR E. RITTENHOUSE, OF HONEOYE FALLS, NEW YORK, ASSIGNOR TO THE A. E. RITTENHOUSE CO., INC., OF HONEOYE FALLS, NEW YORK, A CORPORATION OF NEW YORK

DESIGN FOR AN INSECT EXTERMINATOR

Application filed May 4, 1932. Serial No. 43,708. Term of patent 7 years.

To all whom it may concern:

Be it known that I, ARTHUR E. RITTENHOUSE, a citizen of the United States of America, residing at Honeoye Falls, in the county of Monroe and State of New York, have invented a new, original, and ornamental Design for an Insect Exterminator, of which the following is a specification, reference being had to the accompanying drawing, forming a part thereof.

In the drawing:

The figure is a front elevation of an insect exterminator showing my new design. The design has a circular cross-section throughout.

I claim:

The ornamental design for an insect exterminator, as shown and described.

ARTHUR E. RITTENHOUSE.
